(57) **CLAIM**

We claim the ornamental design for a surgical instrument, as shown and described.

DESCRIPTION

FIG. 1 is a top, front, right isometric view of a surgical instrument showing our new design;

FIG. 2 is a bottom, rear, left isometric view thereof;

FIG. 3 is a front view thereof;

FIG. 4 is a right side view thereof;

FIG. 5 is a rear view thereof;

FIG. 6 is a left side view thereof;

FIG. 7 is a top view thereof; and,

FIG. 8 is a bottom view thereof.

The broken lines shown in FIGS. 1-3 and FIGS. 5-8 illustrate portions of the surgical instrument that form no part of the claimed design.

The shade lines in the Figures show contour and not surface ornamentation.
